CLAIM

The ornamental design for a scent diffuser, as shown and described.

DESCRIPTION

FIG. 1 is a front, side and top perspective view of a scent diffuser showing the new design;

FIG. 2 is a front elevation view thereof;

FIG. 3 is a rear elevation view thereof;

FIG. 4 is a side elevation view thereof;

FIG. 5 is a bottom plan view thereof;

FIG. 6 is a front elevation view thereof in an open configuration; and,

FIG. 7 is a side elevation view thereof.

The broken lines in the drawings show portions of the scent diffuser that form no part of the claim.

1 Claim, 7 Drawing Sheets
